(57) **CLAIM**

I claim the ornamental design for the supplemental awning restraint, as shown and described.

DESCRIPTION

FIG. 1 is a side view of the supplemental awning restraint in the closed position;

FIG. 2 is a side view of the supplemental awning restraint in the unlocked position;

FIG. 3 is a perspective view of the supplemental awning restraint;

FIG. 4 is a front view of the receiver portion of the supplemental awning restraint;

FIG. 5 is a front view of the locking portion of the supplemental awning restraint;

FIG. 6 is a top view of the supplemental awning restraint, the bottom view being substantially identical;

FIG. 7 is a side view of the supplemental awning restraint, the other side being substantially identical; and,

FIG. 8 is a rear view of the receiver portion of the supplemental awning restraint.

The broken lines are shown for illustrative purpose only and form no part of the claim design.
